WINDOW VENTILATOR

Edwin W. Friedholdt, Jr., Chicago, Ill.

Application November 10, 1934, Serial No. 752,499

10 Claims. (Cl. 98—96)

My invention relates to the windows of dwellings, factories and other buildings, and more particularly to ventilators therefor, and my main object is to provide a ventilator which is readily applicable to any window installation whereby to permanently convert the same into a ventilated window.

A further object of the invention is to provide a ventilator which permits various adjustments and degrees of ventilation while making the window safe against unauthorized entrance, or burglar proof in the popular sense.

A still further object of the invention is to design the novel ventilator with means to fully seal it against drafts or seepage of air when it is closed, that it may serve as a perfect closure when it is not in use as a ventilator.

Another object of the invention is to so construct and apply the novel ventilator that it does not weaken but rather reinforces the window.

An additional object of the invention is to construct the novel ventilator along lines of simplicity and rigidity, whereby to permit it to be manufactured inexpensively and to serve efficiently over a long period.

With the above objects in view, and any others which may suggest themselves from the description to follow, a better understanding of the invention may be had by referring to the accompanying drawings, in which—

Figure 1 is an elevation of a typical window equipped with the novel ventilator as seen from without;

Figure 2 is a similar view, as seen from within;

Figure 3 is an enlarged vertical section of Figure 2 to the extent covered by the ventilator, showing the latter closed and omitting a fly screen attachment;

Figure 4 is a view similar to Figure 3, showing the ventilator open;

Figure 5 is a section on the line 5—5 of Figure 3;

Figure 6 is an elevation of a double type of window to which ventilator units of the character considered are applied.

Figure 7 is an enlarged sectional view taken substantially on the line 7—7 of Figure 2.

As mentioned, the novel ventilator is intended to be installed as a unit in a window. Thus, it is applicable in the lower part of the inner sash by removing a part of the glass and installing the ventilator unit as a substitute; or the entire pane of the sash may be removed and another one containing the ventilator unit

substituted, rendering the ventilator an easy replacement for any window sash.

Referring specifically to the drawings, a typical window sash is shown in Figures 1 to 4, the upper and lower rails thereof being indicated at 10 and 11, while the stiles are indicated at 12. The preferred ventilator installation is of the double visor type and built in a rectangular frame having upper and lower bars 13 and side pieces 14 connecting the bars. These parts are 10 made of flat material, and the spacing of the side pieces 14 is such as to leave some room between the sides of the ventilator and the sash stiles 12 for the fitting of glass inserts 15. The ventilator is also preferably spaced somewhat 15 from the lower sash rail 11, to permit the fitting of a bottom glass insert 16 between the ventilator and the rail. While the ventilator could extend fully across the sash and to the bottom rail thereof, I prefer to provide the marginal 20 glass inserts to serve as supplements of the window pane and permit more light to enter. Also, with the ventilator manufactured as a unit, its top and bottom bars 13 could be made of extra length so as to be trimmed off at any 25 point desired to fit different widths of sashes. Thus, the ventilator can be adapted to such sashes without being altered in its vital construction. Of course, after the length of the bars 13 for any installation has been determined, 30 the glass inserts 15 and 16 can easily be cut to size.

As indicated in Figure 5, the material of the ventilator frame is channeled in its external marginal edges as indicated at 17 and fitted 35 with lead channel strip inserts 11a to receive the window pane and other glass elements and form weather proof joints therewith. The glass elements are aligned with the ventilator frame by being marginally encased in a metallic channel frame 18 which seats like the window pane in the sash and receives the putty seal on the outside.

The side pieces 14 of the ventilator frame are extended with vertical rearward strips 19 which 45 terminate the inward bends 20. Inside the upper ends of the strips 19 are disposed pieces 21 which are formed with arcuate grooves 21a, these forming cams for the travel of pins 22 carried in bearings 23 which extend from the 50 upper bar 24 of a visor frame 25. The pins 22 not only act as pivots for the visor to swing out from below as indicated in Figure 4, but the cam slots 21a also provide room for a rising and falling movement on the part of the visor. In- 55

cidentally, the pins 22 are threaded through the bearings 23, so as to be retractable from the cam pieces 21 and permit the removal of the visor; and the pins have external and slotted heads 5 as seen in Figure 4 to permit the pins to be adjusted by means of a screw driver.

The visor frame 25 is principally constructed along the lines of the ventilator frame in that it is channeled and fabric-insulated in respect 10 to a glass sight 25a. The swing of the visor is controlled by the familiar type of spacer bracket 26 which is longitudinally slotted at 26a to receive the neck of a bolt 27 whose shank passes through a flange 28a of the bend 20 to receive 15 an adjusting cap nut 28. It is seen in Figure 3 that the bracket 26 folds close to the ventilator when its visor is closed, so as not to be in the way.

The visor frame is specially constructed to permit 20 the insertion and removal of the glass sight 25a. As seen from without, the sides and bottom of the frame take a U-shaped unit 25b which is secured by means of screws 29 to the stock of the frame. As the external unit forms 25 a part of the channel receiving the glass sight, it follows that the removal of the screws 29 enables 30 the outer unit to be taken off, so that the glass can be easily removed or inserted. The peculiarity of the visor frame also extends to its 35 relation with the top bar 13 of the ventilator frame and bar 24a of a visor next below the one just described. In other words, the first-described visor is intended to close in relation to the said bars in a manner to both permit the 40 easy operation of the upper visor, yet enable it to be tightly closed when swung in. For the purpose specified, the top bar 24 of the upper visor is formed with a rear upstanding angle strip 24c in order to interlock with a similar 45 downward formation or flange 13a of the bar 13 when the visor rises into closed position. A fabric weather strip 24d is carried on the inner side of the strip 24c in order that the closure so formed may be weather proof. When the 50 visor has been closed as described, its bottom bar fits in the angle formed by the bar 24a with a rear upstanding extension 24d of its own, the receiving side of the latter also carrying a strip 55 of insulating fabric 24e. Thus, an interlocking seal between the upper visor and the top bar of the ventilator has been provided; also, a similar seal between the meeting bars of the visors is had. In addition, the sides of the visors are sealed to the sides of the ventilator frame, and 60 the bottom of the lower visor to the bottom of the ventilator frame, by forming the side and bottom bars of the latter with an outwardly facing channel 13d containing a felt filler 13c. Thus the sides of the visor sections 25b and the 65 bottom of the same in the lower visor shut against the filler 13c when the visors are closed.

The vertical bends 20 at the sides of the ventilator frame are supplemented by a bottom section 20a and sufficiently spaced from the visors to permit the insertion of a fly screen 30 which is grooved in its side and bottom edges from the high position indicated by dotted lines in Fig. 2 to the full line position, the screen 70 receiving the bends and said section in its grooves as it is slid down. It is seen that the ventilator visors may be operated individually or jointly without being affected by the fly-screen. If desired, the fly-screen may be replaced by a frame formed with inwardly project-

ing ventilator louvers, these being more suitable to check drafts in colder weather.

It will be seen from the above description that I have provided a ventilator which is easily applicable as a unit to any type of window. In fact, it may be made much narrower than shown, whereby to serve fully as a substitute for a window pane in a double window such as shown in Fig. 6, or a French window. The ventilator does not require any change in window design or construction as it does not depend in any manner on the form of the window, but may be dimensioned to suit a variety of window widths as was previously explained. The ventilator would occupy a height of less than one-third in a sash of conventional height, although a shorter sash has been shown in the drawings because of lack of space, this feature indicating that an ample amount of light through the sash is allowed despite the presence of the ventilator. The visor attachments permit various degrees of ventilation to pass through the ventilator without occasioning direct drafts. Yet, additional protection may be had by the provision of a slide containing fly netting, louvers, or even an exhaust fan in case this type of ventilation is desirable.

The novel ventilator is preferably constructed of copper strip material or of such other metal as may withstand weather conditions or the effects of water seepage when the window is washed. In this connection, it is seen that the novel ventilator does not present obstructions to the window washing operation. Further, when the window has been locked, the ventilator provides no access to anyone seeking an unauthorized entrance, as the visor openings are narrow and remote from the locking zone of the window sash. While the ventilator may be applied to any window in a dwelling or other building it is preferable to install it in a window which is usually kept closed or locked so that proper ventilation may be had without the necessity of unlocking or opening the window. Finally, it will be appreciated that the novel ventilator is neatly constructed along lines of simplicity and 45 rigidity.

I claim:—

1. A window ventilator comprising a rectangular frame, visor elements carried by said frame, spaced channel flanges along the sides and bottom of the frame on the inner side of the ventilator and a fly-screen frame grooved in its sides and bottom, the flanges forming guides to receive the screen frame as a slide.

2. A ventilator for windows comprising a frame insertable in the window sash, the upper bar of the frame being of rectangular cross-section and with a pendent outer flange, a visor swingably mounted on said frame, said visor having an upper bar of angular cross-section seating the upper bar of the frame when the visor is closed, said flange of said frame overlapping the upper bar of said visor, cams carried by the ventilator frame at the sides, and hinge pins carried by the visor and traveling in the cams, the course of the cams being such as to lower the visor to clear said outer flange before it can be swung out.

3. A ventilator for windows comprising a frame insertable in the window sash, the upper bar of the frame being of rectangular cross-section, and with a pendent outer flange, a visor swingably mounted on said frame, said visor having an upper bar of angular cross-section seating the upper bar of the frame when the

visor is closed, said flange of said frame overlapping the upper bar of said visor, cams carried by the ventilator frame at the sides, and hinge pins carried by the visor and traveling in the cams, the course of the cams being arcuate whereby to lower the visor in an outward course to clear said outer flange before it can be swung out.

4. A window ventilator insertable in the pane of a window and comprising a rectangular frame, upper and lower individually framed visor elements mounted in said frame for independent swinging movement, the upper bar of the upper visor frame and the upper bar of the 10 ventilator frame being engageable to form a closure, the lower bar of the lower visor frame and the lower bar of the ventilator frame being similarly engageable to form a closure, and the respective bottom and top bars of the upper 15 and lower visor frames being engageable to form 20 a closure.

5. The structure of claim 4, the meeting bars of the visors being of angular cross-section whereby to cause the visors to engage with each 25 other.

6. A window ventilator comprising a unit adapted to replace a portion of the pane in a window sash, said unit including a rectangular frame having top, bottom and side bars, said 30 top and bottom bars being extended beyond said side bars, the free ends of said extended bars being adapted for rigid seating in the stiles of said sash, and the inner edges of said extended portions of said top and bottom bars being 35 formed to support transparent glazed panels therebetween.

7. The structure of claim 6, and the upper 40 edge of the top bar and lower edge of the bottom bar being formed to provide longitudinally extending channel portions to seat the free edges of the remaining sash pane portions.

8. A window ventilator comprising a unit adapted to replace a portion of the pane of a window sash, said unit including a rectangular

frame having top, side and bottom bars, said top and bottom bars being extended beyond said side bars, the free ends of said extended bars being adapted for being rigidly seated in the stiles of said sash, the inner edges of said extended portions of said top and bottom bars supporting glazed transparent panels therebetween, and a channel frame along and seated in the inner sides of at least the stiles of the sash, said frame receiving the outer edges of 10 the sash pane portions and glazed panels as well as the free ends of said top and bottom bars to align such pane portions, panels and bars into a common plane.

9. A window ventilator adaptable for installation in a window sash of any normal width, said 15 ventilator comprising a unit adapted to replace a portion of the sash pane, said unit comprising a rectangular frame having top, bottom and side bars, said side bars being spaced apart a 20 distance less than the width of a sash of minimum normal width, the top and bottom bars of said frame being extended laterally beyond said side bars a distance sufficient to permit the outer ends of said top and bottom bars to seat 25 in the stiles of a sash of maximum normal width, the facing edges of said extended portions of said top and bottom bars being formed to support glazed transparent panels therebetween, and movable ventilation control means 30 carried by said frame between said side bars.

10. A window ventilator comprising a unit adapted to replace a portion of a window sash pane, said unit including a rectangular frame having top, bottom and side bars, said top and 35 bottom bars being extended beyond said side bars, the free ends of said extended bars being adapted for being rigidly seated in the stiles of said sash, panels carried between the facing edges of the extended portions of said top and bottom bars, and movable ventilation control means carried by said frame between said side 40 bars.

EDWIN W. FRIEDHOLDT, JR.
